CHARLES JULIUS KLEIN, OF NEW YORK, N. Y., ASSIGNOR TO RALPH A. SCHOENBERG, OF NEW YORK, N. Y.

ELECTRICAL APPARATUS.

No. 891,263.

Specification of Letters Patent.

Patented June 23, 1908.

Application filed May 7, 1907. Serial No. 372,320.

To all whom it may concern:

Be it known that I, CHARLES J. KLEIN, a citizen of the United States, residing in the borough of Manhattan, in the county of New York, city and State of New York, have invented certain new and useful Improvements in Electrical Apparatus, of which the following is a specification.

This invention relates to electrical apparatus, and particularly to electrical apparatus or devices termed "cut-outs", which ordinarily comprise a box or receptacle or what may be termed a plug receptacle and a plug, the entrance of which latter into which former, they being both provided with contacts, terminals or other circuit members, closes or extends an electrical circuit, dependent upon the union of the plug with an electrical lamp heater or other translating or consuming device or apparatus. By the provision of a plurality of the boxes or receptacles at convenient points, the connection of the translating or consuming device or apparatus with a current-supply line may be effected at a number of desirable points in a building, to permit of the attachment of the plugs at predetermined places.

In the prior art it is old to have a box or receptacle provided with closure means for the box or receptacle or the face-plate of the same, which closure means open inwardly of the box or receptacle upon insertion of the plug; such closure means returning automatically to normal or operative position.

According to the present invention, I provide a box or receptacle having closure means opening upon the insertion of the plug, but not opening inwardly of the box or receptacle. In so opening, the closure means open either outwardly of the box or receptacle or in a plane extending neither inwardly nor outwardly of the box or receptacle.

The present invention, as above outlined, has for its object to provide improved apparatus or devices of the character referred to which will be relatively simple and inexpensive in construction, convenient in installation and use, effective in operation, neat in appearance, and generally superior in point of efficiency and adaptability to varying conditions of use; and which, by dispensing with inwardly opening closure means and the necessity of providing for the reception of the same within the box or receptacle, may

still be constructed so as to present a substantially flush appearance when the plug is not connected with the receptacle and also, if desired, when the plug is applied to the box or receptacle.

The improvements have all the desired advantages of normally maintaining the plug-opening closed to prevent entrance of foreign substances into the said box or receptacle, which would cause deterioration of the circuit conditions and tend to cause short circuiting.

In that form of construction embraced within the present invention in which the closure means open outwardly upon the insertion of the plug, they may be formed and caused to closely associate themselves with the plug so as to obviate any unsightly or inconvenient projection or obstruction.

In the drawings:—Figure 1 is a longitudinal sectional view of a box or receptacle and plug therefor constructed and associated according to the present invention the plug being shown partly in elevation; Fig. 2 is a vertical sectional view of the same, taken upon the line 2—2, Fig. 1; Fig. 3 is a top plan view of the box or receptacle, the plug having been detached therefrom; Fig. 4 is a fragmentary bottom plan view of the same; Fig. 5 is an enlarged transverse sectional view, taken upon the line 5—5, Fig. 4, looking in the direction of the appended arrow, the closure means being shown in open position in dotted lines; Fig. 6 is an enlarged fragmentary detail sectional view, taken upon the line 6—6, Fig. 4; Figs. 7, 8 and 9 are enlarged fragmentary perspective views of members of the closure means.

Corresponding parts in all the figures are denoted by the same reference characters.

Referring with particularity to the drawings, the general reference character A in each of the figures where employed designates the box or receptacle preferably formed of insulating material, the reference character B designates the plug, the reference character C designates the face-plate of the box or receptacle, and the reference character α designates the inner wall of the box or receptacle, the reference character D designating the building wall or other construction in which the box or receptacle is installed.

Referring to Figs. 1 to 9 inclusive, the box or receptacle A is provided at its inner wall α with contacts or terminals 17 and 18 re-

spectively which are spaced apart and connected with the usual line wires 19 and 20. These contacts are arranged to receive the plug B upon its insertion through the plug-opening 21 in the face-plate C, which said plug-opening is provided with the closure means E. Said closure means E comprise two members, e and f, which members are arranged adjacent to and in position to close the plug-opening when the plug is not passed through the latter. Each of the members consists of an elongated, concave or dished plate or shutter 24, of such formation that the two members when assembled, and in the plug-opening closing position, constitute a cup-shaped entirety, having inner or lower meeting or joining edge portions 25 and outer or upper spaced edge portions 26, which latter form a substantially continuous rim of the cup-shaped formation of the associated members e and f, said edge portions 26 extending substantially in the same plane and substantially flush with the outer surface of the face-plate C when the said closure means members are in plug-opening closing position. The longer portions 26^a of the edge portions 26 extend preferably in parallelism, whereas the shorter portions 26^b of the edge portions 26 are of such curvature as to be merged in a combined curvature of the end portions of the plates or shutters 24. With the members e and f in plug-opening closing position, as shown in Figs. 3, 4 and 5, in full lines, said members project or dip inwardly or downwardly from the face-plate C, and are conveniently housed within the box or receptacle A at the outer or upper portion of the same.

F designates means supporting and relatively movably connecting the members e and f, and G designates tension means affecting the members e and f and tending to maintain the same in plug-opening closing position.

The means F for supporting and relatively movably connecting the members e and f comprises, in a preferred form of construction, two spaced pins or end-bearings 27, which are secured beneath the face-plate C at opposite ends of the elongated plug opening 21, by means of the bearings 28, 28. The free ends of the pins 27, 27 project towards each other and terminate beneath the plug opening 21 where said free ends pass through ears 29 upon the plate or shutter of the member f, and through other ears 30 upon the plate or shutter of the member e, the ears 29 underlapping the ears 30 by being bent slightly inwardly, as at 31, as clearly shown in Figs. 3, 7, 8 and 9; said ears being formed in the outer or upper edge portions 26 of the plates or shutters 24, and in the end portions 26^b thereof. The plates or shutters 24 are free to move pivotally upon the pins 27 and 65 to project outwardly or upwardly of the face-

plate C, as the edge portions 25 of the said plates or shutters relatively separate, and the edge portions 26 thereof approach each other, as most clearly shown in Fig. 2. The concavity or curvature of the plates or shutters 24 is such, and the confines of the plug-opening 21 are so correspondingly formed, that when the plates or shutters constituting the members e and f move outwardly through the plug-opening 21 the outer surface portions of the members e and f continue during such movements substantially in close sliding engagement with the confines of the plug-opening 21, thus opening the plug-opening only between said members e and f as necessary for or caused by the insertion of the plug between said members.

The tension means G are applied to the means F and to the members e and f, and comprise two coil springs, 31 and 32 respectively, the spring 31 being coiled around one of the pins 27, bearing at one end, as at 33 upon the pin 27 at its point of connection 28 with the face-plate C, and at the other end, as at 34, upon the adjacent end portion of the member e. The spring 32 is coiled around the other pin 27, bearing at one end, as at 35 upon the pin 27 at its point of connection 28 with the face-plate C, and at the other end, as at 36 upon the adjacent end portion of the member f. The springs 31 and 32 are adapted to force the inner edge portions 25 of the members e and f into engagement to maintain the closure means E in position within the box or receptacle and in cup-shaped form in entirety.

The plug B comprises an insulating body portion 37 which is bifurcated to constitute spaced prongs 38 carrying elongated contacts, 39 and 40 respectively, which are adapted to be engaged with the contacts 17 and 18 respectively within the box or receptacle. The plug B is further provided with a crown 41 provided with a neck 42 through which extend service wires 43 and 44, which are respectively connected with the contacts 39 and 40 of the plug.

The operation, method of use and advantages of the improvements constituting the present invention will be readily understood from the foregoing description taken in connection with the accompanying drawing and the following statement:—Referring to the form of construction shown in Figs. 1 to 9 inclusive, the members e and f of the closure means E normally lie within the box or receptacle A or within the outer surface of the face-plate C, forming together a cup-shaped entirety concave with relation to the face-plate. The members e and f are maintained in closing position by the tension means G, effectually closing the plug-opening 21. If, now, the plug B be passed through the plug-opening and brought to bear upon the curved surfaces of the members e and f, continued

inward pressure will cause the meeting edge portions 25 of the members *e* and *f* to relatively separate, permitting the plug to pass between said members inwardly of the box or receptacle until the contacts 39 and 40 upon the plug are brought into engagement with the contacts 17 and 18 within the box or receptacle. The relative separation of the edge portions 25 of the members *e* and *f* is accompanied by relative approach of the edge portions 26 of said members *e* and *f* which edge portions are forced outwardly through the plug-opening 21, coming finally into engagement with the sides of the plug B beneath the cap or crown 41 thereof, and thus limiting the inward movement of the plug. The edge portions 25 of the members *e* and *f* also bear upon the sides of the plug within the box or receptacle, under urging of the tension means *G*. The members *e* and *f* in their outward pivotal movement remain in close engagement with the confines of the plug-opening 21, and when the plug is home in the box or receptacle the said plug-opening is completely filled by the plug and the members *e* and *f*. The tension means *G* acting through the members *e* and *f* act upon the plug B to hold it in the box or receptacle. When the plug is withdrawn from the box or receptacle, the tension means *G* cause the members *e* and *f* to move pivotally to bring the inner edge portions 25 of the members *e* and *f* into engagement within the box or receptacle, completing the cup-shaped formation of the entirety and again effectually closing the plug-opening, the edge portions 26 of the members *e* and *f* resuming their position substantially flush with the outer surface of the face-plate *C*. It is thus apparent that without using closure means for the plug-opening which open inwardly of the receptacle and are operated by the insertion of the plug, the invention provides effective, neat and efficient closure means operated by the insertion of the plug to open the plug-opening, and automatically closing the plug-opening upon the withdrawal of the plug, the closure means, on the contrary, opening outwardly of the receptacle, but not extending outwardly to an extent to cause any material projection or obstruction.

In the form of construction disclosed and described, closure means are provided effectually closing the plug-opening when the plug is out of the box or receptacle, which do not open inwardly of the box or receptacle although such means are operated by the insertion of the plug, and which serve effectually to close the plug-openings against the entrance of dirt, moisture or any other foreign substance, such closure means operating automatically and requiring no manipulation distinct from the insertion and withdrawal of the plug. It is manifest that the number of closure means or the members thereof are in

proportion to the number of plug-openings employed.

Finally, I do not desire to be understood as limiting myself to the specific construction, combination and operative association of parts and members as shown and described, but reserve the right to vary the same, in adapting the improvements to varying conditions of use, without departing from the spirit of the invention or the terms of the following claims.

Having thus described my invention, I claim and desire to secure by Letters Patent:—

1. Improvements of the character described, comprising a plug receptacle provided with closure means opening outwardly of the box or receptacle and operated by the insertion of the plug.

2. Improvements of the character described, comprising a box or receptacle provided with a face-plate having a plug-opening therein; and closure means for said plug-opening opening outwardly of said box or receptacle and operated by the insertion of the plug.

3. In a device a plug receptacle of the class described, a face-plate therefor having a plug opening therein and a spring actuated curved shutter movably mounted adjacent said plug opening and adapted to be actuated by the insertion of a plug to project outwardly through said plug opening.

4. In a device a plug receptacle of the class described, a face-plate therefor having an opening therein, and a plurality of shutters pivoted adjacent to said opening and adapted to open outwardly upon the insertion of a plug.

5. In a device a plug receptacle of the class described, a face-plate therefor having an opening therein, and a plurality of curved shutters pivoted adjacent to said opening and adapted to open outwardly upon the insertion of a plug.

6. In a device a plug receptacle of the class described, a face-plate therefor having an opening therein, a plurality of shutters pivoted adjacent to said opening and adapted to open outwardly upon the insertion of a plug and means for normally actuating the shutters to close the opening in the face-plate.

7. In a device of the class described, a plug receptacle, a face plate on the same provided with an opening, and means for closing said opening, said means swinging outwardly of the plug receptacle and operated by the plug which co-operates with the box or receptacle.

8. In a device of the class described, a plug receptacle, a face-plate for the same having an opening, a pivoted concave shutter adapted to swing in a vertical plane, and means to normally cause the shutter to close the opening in the face-plate, said shutter being

adapted to open upon the insertion of the plug.

9. In a device of the class described, a plug receptacle provided with an apertured face-plate, and means for closing said aperture, said means embodying a pivoted actuated member arranged to be swung outwardly of the receptacle and adapted to be actuated in one direction by the insertion of the plug.

10. In a device of the class described, a plug receptacle provided with a face-plate provided with a plug opening, means for closing said opening, said means embodying a pivoted actuated member arranged to be swung outwardly of the receptacle and adapted to be actuated in this movement by the insertion of the plug, and means for normally causing the closure member to close the opening in the face-plate.

11. In a device of the class described, a plug receptacle provided with a face-plate provided with an opening, and means for closing said opening, said means comprising two oppositely disposed pivoted tensionally

actuated members adapted to be swung outwardly of the receptacle and adapted to be actuated in this direction upon the insertion of the plug.

12. In a device of the class described, a face-plate having a plug opening therein and a spring actuated shutter movably mounted adjacent said plug opening and adapted to be actuated by the insertion of a plug to project outwardly.

13. In a device of the class described, a plug receptacle a face-plate therefor having an opening therein, and a plurality of shutters pivoted adjacent to said opening and adapted to open outwardly upon the insertion of a plug.

In testimony whereof, I have signed my name to this specification in the presence of two subscribing witnesses.

CHARLES JULIUS KLEIN.
